UNITED STATES PATENT OFFICE

HERBERT H. MOOR, OF ROCK ISLAND, ILLINOIS

DESIGN FOR A TOY

Application filed March 25, 1931. Serial No. 39,235. Term of patent 7 years.

To all whom it may concern:

Be it known, that I, HERBERT H. MOOR, a citizen of the United States, residing at Rock Island, in the county of Rock Island and State of Illinois, have invented a new, original, and ornamental Design for a Toy, of which the following is a specification, reference being had to the accompanying drawings, forming a part thereof.

I claim:

The ornamental design for a toy, substantially as shown and described.

In testimony whereof I affix my signature.

HERBERT H. MOOR.
